UNITED STATES PATENT OFFICE.

CHARLES W. McCORMICK, OF EMPORIA, KANSAS, ASSIGNEE TO LAMSON CONSOLIDATED STORE SERVICE COMPANY, OF NEWARK, NEW JERSEY, A CORPORATION OF NEW JERSEY.

STORE-SERVICE APPARATUS.

SPECIFICATION forming part of Letters Patent No. 781,896, dated February 7, 1905.

Application filed May 27, 1903. Serial No. 158,914.

To all whom it may concern:

Be it known that I, CHARLES W. McCORMICK, of Emporia, in the county of Lion and State of Kansas, have invented certain new and useful 5 Improvements in Store-Service Apparatus, of which the following is a specification.

My invention relates to new and useful improvements in store-service apparatus; and its object is to produce an apparatus capable 10 of carrying cash and parcels.

My invention consists of certain novel features hereinafter described, and particularly pointed out in the claims.

In the accompanying drawings, which illustrate a construction embodying my invention, Figure 1 is a side elevation of the apparatus, showing the carrier at the salesman's station. Fig. 2 is a similar view to Fig. 1, showing the carrier at the cashier's station or central station. Fig. 3 is a detail view, partly in section, of the carrier. Fig. 4 is a detail view, partly in section, of part of the carrier with the receptacle in position to be despatched. Fig. 5 is an end plan view of the carrier. Fig. 6 is an end elevation of the receptacle, showing the same closed in full lines and open in dotted lines. Fig. 7 is a top plan view of the receptacle closed. Fig. 8 is a detail view, partly in section, hereinafter described. Fig. 9 is a side elevation of part of the propelling mechanism, hereinafter described.

Like letters of reference refer to like parts throughout the several views.

The wireway A is secured to the hanger B in any desired manner—as, for instance, as shown in Fig. 9 of my Patent No. 721,320—and at its opposite end in any suitable manner to the casting C. Secured near the lower end of the hanger B is the clamp E, to which 35 is pivoted the forwardly-extending arm D' and held in its fixed position by the rod G, secured to the arm D at G' and to the hanger B at G''. The forward end of said arm D is supported by the wires G³ G⁴, connected to 40 the bracket H at G⁵. In the lower opposite ends of said bracket H are two pulleys H', around which passes the propelling-cord J, which extends rearwardly around the pulleys

K⁷, then down and around the pulleys K' in the bracket K², up and around the pulleys K³ 50 in the swinging bracket K⁸, and down and connected to the block K⁴. This arrangement of the propelling-cord and pulleys is similar to that shown in my above-mentioned patent with the exception that in the device shown 55 in the present application the bracket K⁸ is pivotally mounted on the bracket K⁷. This bracket K⁸ is pivoted so that when the handle K⁵ is pulled backward or forward by the operator, as indicated in Fig. 9, it follows the 60 direction of the pull of the cord, and thus prevents the chafing of the cord.

The receptacle L for the cash or parcels, especially adapted for the carrying of gloves, and which passes from the salesman's station 65 to the cashier's or central station, where the gloves or other parcels are wrapped up and the change returned to the salesman, consists of two sections M³, of wire network, secured to the side pieces m m', provided at their upper ends with semicircular pieces M⁴ M⁵, which are connected together by the shaft N, extending through the lugs M¹¹ M¹² of the side pieces M³ and through lugs M⁸ M¹⁰ of said piece M⁴, Fig. 7. Around said shaft N, between the lugs M⁸ M¹⁰, is the spiral spring M⁶, one end of which presses against the pin M⁷ of the lug M⁸ and the other end of which presses against the pin M⁹ of the lug M¹⁰, and this spring tends to open the two wire sections before the receptacle is connected to the carrier for despatch. The carrier M is of the usual construction, provided with the wheels M', adapted to run on the wireway A, and in its lower part with a spring-pressed 85 plate M² and at its extreme lower end provided with an internal flange N², provided with two slots N', as shown in Figs. 3 and 5. When the receptacle is to be despatched from one end of the line to the other, it is connected to the carrier for this purpose by passing the ends of the shaft N through the slots N' and with the carrier transverse to the line and by giving the receptacle a quarter-turn it is brought parallel to the line, and at the 90 same time one end of the shaft strikes the pin 95

N³, so that the carrier is held in proper position with relation to the track-wire. The spring-pressed plate M when the receptacle is inserted, as shown in Fig. 4, presses on the 5 upper ends of the side pieces M⁴ M⁵, holding the same firmly, in connection with the flange N², closed and in fixed position to the carrier. When it is desired to remove the receptacle, it is turned a quarter-turn to bring the ends 10 of the shaft over the slots N' and removed by pulling down. The carrier is retained at the salesman's station by the flat springs K⁶, secured in the usual manner, and at the cashier's or central station by the flat springs L', 15 of the usual construction, secured to the casting C by suitable bolts. This casting C is located on the pin L² and held in fixed position by the set-screw L³. This pin L² is part 20 of the sleeve L⁴, adapted to be adjusted on the post L⁶, carried by the clamp L⁸, suitably secured on the cross-tube L⁷. This cross-tube is supported by the hanger L¹⁰ with the usual 25 clamp L⁹. To this cross-tube L⁷ any desired number of lines may be secured by means of the sleeves and clamps, similar to the sleeves L⁴ and clamps L⁸. The sleeves L⁴ may be 30 adjusted and set by the set-screw L⁵ so as to run into the cashier's or central station from different points and affords an accessible and efficient arrangement for securing any number 35 of lines at the central station diverging at different parts of the store.

Having thus described the nature of my invention and set forth a construction embodying the same, what I claim as new, and desire to secure by Letters Patent of the United States, is—

1. In a store-service apparatus, a way, a carrier adapted to travel on said way, and a 40 removable receptacle connected to said way and consisting of two sections pivoted together and provided with means for opening said sections when removed from the carrier.

2. In a store-service apparatus, a way, a 45 carrier adapted to travel on said way, and a removable receptacle connected to said way and consisting of two sections pivoted together and provided with yielding means for opening 50 said sections when removed from the carrier.

3. In a store-service apparatus, a way, a carrier adapted to travel on said way, and a removable receptacle connected to said way and consisting of two sections pivoted together 55 at their upper ends and provided with means for opening said sections when removed from the carrier.

4. In a store-service apparatus, a way, a

carrier adapted to travel on said way, and a removable receptacle connected to said way and consisting of two sections pivoted together at their upper ends and provided with yielding means for opening said sections when removed from the carrier.

5. In a store-service apparatus, a way, a carrier adapted to travel on said way, a removable receptacle connected to said way and consisting of two sections, a common shaft on which said sections are pivoted at their upper ends, and a spring around said shaft and adapted to open said sections when the receptacle is removed from the carrier.

6. In a store-service apparatus, a way, a carrier adapted to travel on said way, a removable receptacle connected to said way and consisting of two sections, a common shaft on which said sections are pivoted at their upper ends, a spring around said shaft and adapted to open said sections when the receptacle is removed from the carrier, and means on the carrier for holding said sections closed when the receptacle is connected to the carrier.

7. In a store-service apparatus, a way, a carrier adapted to travel on said way, a removable receptacle connected to said way and consisting of two sections, a common shaft on which said sections are pivoted at their upper ends, a spring around said shaft and adapted to open said sections when the receptacle is removed from the carrier, and means consisting of a spring-pressed plate and inward flange on said carrier for holding said sections closed when the receptacle is connected to the carrier.

8. In a store-service apparatus, a way, a hanger for supporting said way, a carrier adapted to travel on said way, a propelling-cord, pulleys around which said propelling-cord is arranged, a handle for operating said cord, and a pivoted pulley-block on the lower 100 end of said hanger adapted to follow the direction of pull on the cord by said handle.

9. In a store-service apparatus, a way, a casting to which said way is connected, a sleeve for supporting said casting, a post on which 105 said sleeve is adjustably secured, a cross-support carrying said post, and a hanger for supporting said cross-support.

In testimony whereof I have signed my name to this specification, in the presence of two subscribing witnesses, this 16th day of January, A. D. 1903.

CHARLES W. McCORMICK.
